EXTENSION TRACKWAY FOR WARDROBE TRUNKS

Robert A. Totty, Petersburg, Va.

Application May 4, 1944, Serial No. 534,071

3 Claims. (Cl. 190—13)

1

This invention is directed to an improvement in wardrobe trunks, and particularly of the type shown in Patent No. 1,597,888, issued August 31, 1926, with the further provision of means to facilitate the positioning of the successive garments.

Wardrobe trunks of the type with which the present invention is more particularly concerned are provided with means designed to be positioned beyond the front of the trunk and providing a garment receiving and hanging unit on which the garments may be placed in orderly arrangement, with means to retain the garments in such orderly arrangement within the body of the trunk and during transportation or storage of the trunk.

The construction of the garment carrying and holding means generally involves a folding frame, extensible into one position to receive the garments and then folded to exert a pressure on the garments to retain them in their selected positions. The foldable frame includes a pressure bar over which the garments must be lifted in positioning them on the frame. This pressure bar, while a virtual necessity in maintaining a proper disposition of the folding frame and for service in exerting pressure on the garments as finally positioned, when in effective position is directly in the way of the simple sliding application of the garments to the frame, and requires that each garment be lifted over such bar before it can be placed in position on the frame. This is not only inconvenient, but tends to a disarrangement of the garment being placed, requiring additional time to properly adjust the garment after it has been placed on the frame.

The primary object of the present invention is, therefore, the provision of means whereby the garment entrance to the supporting frame is entirely free of any obstruction during application of the garments, and this without sacrificing any advantage of the pressure bar as a brace for the garment frame or as a garment pressure element for the positioned garments.

More specifically the invention is directed to mounting the pressure bar for swinging connection with the garment carrying frame, locking means being provided for locking the pressure bar in place for its usual functions, following its displacement to permit convenient and direct placing of the garments on the frame.

The invention is illustrated in the accompanying drawings, in which:

Fig. 1 is a perspective view with the garment-carrying elements in position to receive the garments, the pressure bar being turned out of the way for convenient handling of the garments.

2

Fig. 2 is a perspective view of a portion of a wardrobe trunk, with the garment-carrying elements in folded position to hold the garments, shown in outline, within the trunk.

Fig. 3 is a plan view of the ends of the garment frame bars, with the pressure bar in operative position.

Fig. 4 is an enlarged sectional view on the line 4—4 of Fig. 3.

Fig. 5 is a sectional detail on the line 5—5 of Fig. 3.

Fig. 6 is a detail view partly in section and partly in elevation of one of the joints.

Fig. 7 is a detailed sectional view on the line 7—7 of Fig. 6.

In order to provide a more complete understanding of the present invention, the general construction of the parts of the complete garment carrying unit will be given, it being understood, however, that in such description the details not directly concerned with the present invention are intended as illustrative only, and that the details of the invention per se are intended to be applied to and for use with any and all types of similar apparatus with which they may co-operate, either directly or with such changes as would involve mere mechanical skill.

As illustrated in the accompanying drawings, the wardrobe trunk 1, of any desired or conventional form, is provided near the top with a frame F, preferably metal, riveted or otherwise securely anchored in position. This frame F, as illustrated in the accompanying drawings, is U-shaped in form with its intermediate bar 1^a in contact with the bottom wall of the trunk 1 and its side bars 1^b in contact with the side walls of the trunk. The bar 1^a closely adjacent to the bars 1^b is provided with the upstanding straps 2 to which are connected the inner ends of the garment-carrying bars 3. Each bar 3 is in two parts, the rear part 4 being anchored at its rear extremity to a strap 2, and at its opposite extremity is supported by a U-shaped bracket 5, one extremity of which is secured to the outer or free end portion of a bar 1^b of the frame F and its opposite extremity being secured to the part 4.

The forward part or section 6 of each of the supporting bars 3 has swinging movement with respect to the associated inner part 4. To provide for this movement in at least one serviceable form, the forward extremity of the parts 4 is longitudinally slotted, as at 7, with a transverse pin 8 intersecting the outer end portion of said slot adjacent to the outer open end of the slot. The part 6 is terminally formed with an upward-

ly facing hook end to engage from below a second pin 11 carried by the part 4 and intersecting the slot 7.

The parts 6 of the garment carrying bars 3 may readily be moved to the rear limit of the slots 9, after swinging the parts 6 to disengage the hooks 10 and pins 11. When the parts 6 are moved to the opposite or forward limit of the slots 7 and the hook ends 10 engaged with the pins 11, the parts 4 and 6 are held in longitudinal alinement for the sliding reception of the garment hangers 12 on which the individual garments are supported.

After the desired garments are in position and moved for support on the parts 4 of the garment carrying bars, the parts 6 of such bars are released to permit downward swinging movement. The purpose of this downward movement is to allow the pressure bar 13 at the outer or free ends of the parts 6 of the carrying bars 3 to bear on the garments with sufficient pressure to hold them in proper condition and place during handling of the trunk. In order that this pressure bar 13 may function regardless of the number of garments supported, means are provided to hold the bar 13 in proper pressure applying position, such means consisting of keeper plates 14, formed with spaced openings 15, into which the ends of locking bars 16 are entered to retain the pressure bar 13 in appropriate relation to the garments.

The locking bars 16 are alined on the front face of the pressure bar 13, slidably fitting in openings in outturned ends 17 of such pressure bar. The inner end portions of the locking bars 16 are slideable within a sleeve 16a on the outer face of the pressure bar 13, at the center thereof. A spring 18 is interposed between the proximate ends of the locking bars 16 to normally bias such bars to locking position. Finger pins 19, connected with the locking bars 16 within the length of the sleeve and projecting to the inner side of the pressure bar 13 through slots 20, provide for conveniently withdrawing the locking bars 16 from locking cooperation with the keeper plates 14.

The present invention is designed to permit the individual garments to be directly and easily applied to or removed from the carrying bars 3 without obstruction to such operations. To this end the pressure bar 13 is pivotally connected by a pin 21 to an outturned end or lug 22 of part 6 of one carrying bar 3, to permit the pressure bar 13 to be swung on this carrying-bar part 6, when otherwise free. The free extremity of the part 6 of the second carrying bar 3 is formed with an outturned end or lug 23, identical with the part 22 previously referred to. A U-shaped hanger 24, Figure 4, is secured to the end or lug 23, one leg 25 of the hanger being secured in contact with the inner face of lug 23, while the other leg 26 of the hanger is arranged in spaced relation to the outer face of lug 23, the spacing being just sufficient to receive the free end portion of the pressure bar 13. The cross bar 27 of the hanger 24 supports the pressure bar 13 flush with the part 6 of the carrying bar 3, and the end portion of the pressure bar 13 fitting within the hanger 24 is provided with a fixed lug 28 to bear against one edge of the outer leg 26 of the hanger 24 when the pressure bar is in operative position, to thus accurately space the parts 6 of the carrying bars 3 relative to each other.

A casing 29 is secured to the outer face of the

part 6 to which the hanger 24 is applied and closely adjacent to such hanger. Slidable in this casing is a latch bolt 30, urged forwardly by a spring 31. A finger piece 32 is carried by the bolt 30 and projects through a slot 32a in the outer wall of the casing 29 for convenient operation of the latch bolt 30, against the influence of the spring 31. The latch bolt 30 extends through registering openings a in the leg 25 of the hanger 24 and the outturned end or lug 23 of the part 6 of the carrying bar, and is projected as a locking nose 33 into the space or socket of the hanger 24 arranged to receive the pressure bar. The latch nose 33 has an uppermost beveled side or edge b and the end portion of the pressure bar 13 received within the socket of the hanger 24 is formed with an opening 34 into which the latch nose 33 automatically enters when the pressure bar 13 is moved into operative position. When the latch nose 33 is withdrawn from cooperation with the pressure bar 13, said pressure bar may be readily lifted and bodily swung on its pivot 21.

From the above description it will be plain that when the pressure bar 13 is in operative position, it serves all its contemplated functions, but that with the improved mounting described, such pressure bar 13, when unlocked at one end may be swung on its pivot 21 and thus caused entirely to clear the space between the outer or free ends of the extended parts 6 of the carrying bars 3 and permit the garments as arranged on their individual hangers 12 to be moved directly onto the carrying bars 3 and then rearwardly onto the fixed parts 4 of such carrying bars 3.

In the particular general form described the garments on their hangers are moved rearwardly on the parts 6 of the carrying bars 3 and onto the fixed parts 4 of such bars. When joint at 7 is broken, the parts 6 swing downwardly and inwardly to cause the pressure bar 13 to bear against the garments suspended from parts 4 of the carrying bars 3 to maintain such garments in smooth flat relation to each other notwithstanding even unusual handling of the trunk. The locking bars 16 are operated to permit their ends to engage in the proper openings 15 in the keeper plates 14 to hold the pressure bar in selected and proper pressure position.

In connection with the improved structure it will be noted that when the parts 6 of the carrying bars 3 and the pressure bar 13 are turned down into garment retaining positions, the outturned ends 22 and 23 of these parts 6 will overlie and ride on the keeper plates 14 and thus prevent any lateral play or rattling of the unit when in final position, regardless of trunk movement.

Having thus described the invention, what is claimed as new is:

1. In a garment storage unit adapted to be mounted within a wardrobe trunk between two side walls thereof and including two garment carrying arms having parts relatively fixed with respect to such walls and parts pivotally supported from said fixed parts, means for aligning the relatively fixed and pivotally supported parts to receive garment hangers and arcuate keeper plates carried by such walls concentric with the pivot centers of the pivoted parts, an outturned lug integral with the free end of each of the pivoted parts, adapted, upon folding movement of the pivoted parts, to be guided over the concave edges of the keeper plates, a one piece pressure bar pivotally connected at one end with one of said lugs for swinging movement on an axis ex-

tending longitudinally of the adjacent pivoted part and adapted to be swung to a position between the free ends of the pivoted parts to have its other end disposed in opposed relation with the other lug, means cooperating with the said other lug to form a hanger for the free end of the pressure bar, and means for releasably securing the said free end of the pressure bar in said hanger, said pressure bar carrying means for establishing a latching connection between its ends and the arcuate keeper plates when the pivoted parts of the carrying arms are swung out of alignment and into position between the said side walls of the trunk.

2. In a garment storage unit for use in wardrobe trunks, including two garment carrying arms adapted to be mounted between two opposing walls of the trunk and each having a fixed part and a pivoted part adapted to be swung to an operative aligned position with respect to the fixed part and an arcuate keeper plate secured to each of said walls concentric with the pivot of the adjacent pivoted part, a lug forming a laterally turned portion of the free end of each pivoted part and adapted to ride over the concave edge of the adjacent keeper plate upon the swinging of the pivoted part into the trunk from the stated aligned position, the free end of each lug being directed toward the adjacent wall, when in opposed relation with respect to the stated concave edge of the keeper plate, a rigid one piece pressure bar having an over-all length less than the distance between the free ends of the out-turned lugs, a pivotal connection between the outer face of one lug and one end of said pressure bar, the other end of the pressure bar being adapted to be brought into position against the outer face of the other lug, with the outturned ends of the lugs extending beyond the ends of the pressure bar, the said ends of the pressure bar being outwardly turned to form ears adapted to have operative opposed relation with respect to the inner faces of the keeper plates when the pivoted parts are swung inwardly from the stated

aligned position, means for releasably connecting the said other end of the pressure bar with the said other lug, and means carried by the pressure bar for projection beyond the said ears for latching connection with the keeper plates, the lugs and the adjacent ears cooperating to form an angle with which the adjacent keeper plate cooperates to effect bracing of the parts.

3. A garment storage unit comprising spaced carrying bars to receive and support individual garment hangers, a pressure bar normally bridging said carrying bars, said pressure bar being pivotally connected at one extremity to one carrying bar to swing on an axis extending longitudinally of such carrying bar, the other carrying bar being formed with a socket to receive the opposite end portion of the pressure bar, means for locking said pressure bar in and relative to said socket, said socket including a U-shaped hanger on the carrying bar having one side outwardly spaced from one surface of such bar to snugly receive the end portion of the pressure bar, and a lug carried by the pressure bar and adapted to engage an edge of the hanger to adjust the relation between the end of the carrying bar and the end of the pressure bar, when the latter is within the socket.
